(57) **CLAIM**

The ornamental design for a device for endoscopic vascular surgery, as shown and described.

DESCRIPTION

FIG. 1 is a perspective view showing the rear side, and the left-hand side of the device for endoscopic vascular surgery according to the invention;

FIG. 2 is a perspective view showing the front side, and the right-hand side thereof;

FIG. 3 is a top plan view thereof;

FIG. 4 is a side elevation view thereof;

FIG. 5 is rear elevational view thereof;

FIG. 6 is a side elevational view thereof, opposite that shown in FIG. 4;

FIG. 7 is front elevational view thereof; and,

FIG. 8 is a bottom plan view thereof.
